UNITED STATES PATENT OFFICE.

WILLIAM L. MORRIS, OF FORT WAYNE, INDIANA, ASSIGNOR TO S. F. BOWSER & CO., INC., OF FORT WAYNE, INDIANA, A CORPORATION OF INDIANA.

LUBRICATING SYSTEM.

1,159,598.

Specification of Letters Patent.

Patented Nov. 9, 1915.

Application filed February 16, 1912. Serial No. 677,919.

To all whom it may concern:

Be it known that I, WILLIAM L. MORRIS, a citizen of the United States, residing at Fort Wayne, in the county of Allen and State of Indiana, have invented certain new and useful Improvements in Lubricating Systems, of which the following is a specification.

The object of the invention is to provide an improved lubricating system for use particularly in connection with machines which circulate too rapidly to filter or purify the same while in use.

Other objects of the invention will appear from the following description of the combination and arrangement of the various elements comprised in my improved circulating and filtration system for oils, the same being also shown in the accompanying drawings forming a part of this specification, and 20 finally set forth more specifically in the appended claims.

In the said drawings, Figure 1 is a perspective view of my improved arrangement of oil containing and circulating apparatus 25 with machines or turbine engines which the system serves, shown in elevation with parts thereof in section, the wiring systems for electric connections being shown diagrammatically; Fig. 2 is a plan view of the reservoirs or tanks for containing a supply of lubricating oil together with the filtration and circulating means immediately attached to the said tanks. Fig. 3 is a detail view of the stand-pipe, gage and heating coil. Fig. 4 is a detail view of a check valve, and Fig. 5 is a view showing the connection of the pump with the turbine.

As illustrated, my improved system is shown and applied to the serving of a plurality of turbine machines, there being three shown in the drawings and designated by the common reference character 10, since each of these turbines may be alike and are so shown. Each turbine 10 is provided with an oil pump shown diagrammatically and indicated in the drawings by the common reference character 11. This pump 11 may be of any desired construction for moving liquids, and it is driven in any desired manner, as by means of a shaft 12 which is rotated by the turbine. The pump 11 is preferably located as shown in the base 13 of each turbine.

14 is a drip pipe through which the used oil from each turbine passes to a strainer

chamber 15. Within the strainer chamber 15 of each of the turbines, suitable means, as indicated by the reference character 16, is interposed for partially clarifying the oil on its way to the drip chamber in the base 13 of each of the turbines, the oil passing to this drip chamber through pipe 17. The oil pump 11 being operated directly by the rotary member of the turbine as shown, takes oil from the interior of the drip chamber 13 in the base of the turbine and delivers the same through pipe 18 to the bearings of the turbine indicated for example, by the reference character 19. Between the bearings 19, however, and the oil pump 11, the pipe 18 is provided with a coil as indicated at 20 which may be passed through a cooling chamber 21. That portion of the pipe through which the oil passes from the cooling chamber to the bearing indicated at 19, is designated by the reference character 22, and there is a check valve 23 interposed in the pipe 22 for controlling the flow of the oil from the pump 11 to the bearings of the machine to be lubricated.

The portion of the circulating system above described, is ordinarily furnished with each horizontal turbine engine, and my invention consists in the various adaptations and arrangements of parts which have been added to the machine and to that portion of their lubricating systems already described, in order to render the same more efficient.

To the pipe connecting the oil pump 11 with the bearings of the turbine to be lubricated, is connected an oil supply pipe 24, which is controlled by a quick throw valve indicated at 25 operated by a lever 26. The valve lever 26 has connected therewith an auxiliary arm 26^a which is provided for the purpose of closing an electric switch between the adjacent terminals of the circuit wires 27, 28 connected to an electric motor 29 designed to operate a pump indicated at 30, which in the embodiment shown, is operated from the motor 29 by a suitable chain 31 connected to a gear on the motor and an intermediate gear as illustrated, which is also geared to a large driving gear 32 on the pump. The motor and the pump 29 and 30 respectively, are preferably located upon the upper side of one of two tanks of like capacity which are indicated by the reference characters 33, 34, preferably some distance from the turbines or other machines to be

served by my improved oiling and filtration system. From pump 30 on the top of the large supply tank 33, a supply pipe 35 extends to and is connected with pipe 36, which serves as a common feed pipe from which the valve controlled supply pipes 24 of each of the turbines conduct lubricant to each of the mechanisms to be lubricated.

The normal operation of a turbine oiling system like that first described and shown, it will be seen, is under the direct control of the turbine itself. As soon as the rotary member of the turbine is operated, the operation of the pump 11 will begin, and if there be a supply of oil in the drip chamber 13 in the base of the turbine, the valve 23 in pipe 22 being open, oil will be passed by the pump 11 through the cooling chamber 21 and the coil 20 therein to the bearings of the machine, and the drip will pass from the machine into the strainer chamber 15 and thence to the drip chamber 13 to be again taken up by the pump and passed to the bearings to be lubricated. But oil used in this manner rapidly, soon requires treatment different from that afforded by the mechanism described directly connected with each of the machines, and when it is desired to introduce a fresh supply of oil with my improved system, this may be accomplished by operating the valve lever 26 in the supply pipes leading to each of the lubricating systems of the turbines. The operation of the valve lever 26 to open valve 25, will result in moving the branch lever 26 connected therewith into contact with the adjacent terminals of each of the feed wires 27, 28 which will close the circuit to motor 29, and will immediately cause the pump 30 to be operated and a fresh supply of oil from the supply tanks 33, 34 to be pumped through pipes 35, 36 into the feed pipes 24, through valves 25 to the bearings of each of the machines. The supply tanks 33, 34 not only serve the purpose of reservoirs for fresh supplies of lubricant, but are utilized as well in filtering and purifying the oil, and to this end have return drip connections leading from strainer chamber 15 of each of the turbines. This consists of pipe connections indicated at 40 leading from each of the strainer chambers 15, to overflow chamber 41. Within the overflow chamber 41, is the upward terminus of overflow pipes 42, there being one of such pipes to each overflow chamber leading to the common drip main 43 which communicates through pipe 44 with each of the supply tanks 33, 34, such connection being effected through the branch connections 45, 46, the former of which enters the tank 33 and the latter, the tank 34, both of said branches being under the control of a common valve 47, controlled by an operating lever 48, preferably of such a character that the direction of the lever indicates the man-

ner in which the valve is set, so that if the lever 48 be set in the manner indicated in Fig. 1, it will indicate that the valve 47 is open to furnish communication between the drip return pipe 44 and branch 45 with supply tank 33, while if the said lever 48 be moved about 90 degrees or to point toward the supply tank 34, it will indicate that the drip return pipe 44 is open through branch 46 to discharge oil in supply tank 34. By this construction it will be seen that all overflow from the turbines, will be passed from the strainer chamber 15 into overflow chambers 41, and thence through pipes 42, 43, 44, and branches 45, 46 to either of the supply tanks 33, 34, at will.

In like manner, it is desirable that supplies of fresh oil shall be obtainable from either of the supply tanks 33, 34 under the control of pump 30, and to this end the supply pipe 49 leading to pump 30, is provided with the common valve controlled branches 50, 51, which pass downwardly into each of the supply tanks 33, 34 respectively, and terminate near the bottom of said tanks where they are provided with suitable strainers as indicated at 52, 53.

54 designates the valve for controlling the branch feed pipes 50, 51, and 55 designates a suitable valve lever of the same type as the valve lever 48, which is preferably so arranged that the direction of the lever 55 indicates the position of the valve, so that an operator will know, for example, when the valve lever 55 is set in the manner indicated in Fig. 1 pointing toward the tank 33, that the pump 30 is discharging oil from tank 33 into the system, and likewise when this lever is set at about an angle of 90 degrees to the position as shown in Fig. 1, it will indicate that the pump 30 is discharging oil from the tank 34 into the system.

It is obvious that the tanks 33, 34 may be of any desired construction, but it is preferred that they be of the form herein shown, and provided with large manholes having quick operating removable covers as indicated at 60, 61. Each tank is preferably provided with a float operated indicator, the upward portions of which are indicated by the reference characters 62, 63. The height to which these indicator sticks 62, 63 rise above the tops of the tanks, will indicate the quantity of oil in each tank, and these sticks may be provided with convenient designations by which the quantity of oil in the tanks either in lineal measure or in liquid or cubical measure, may be determined. The floats secured to the lower extremities of the indicator sticks 62, 63, are not shown since these indicators are of a common and well known construction, and form no part of the present invention.

In the use of supply tanks of the form and character of the tanks 33, 34, consider-

able quantities of sludge and refuse matter will collect in the tanks. The same may be removed through suitable removable closures or clean-outs, as indicated at 64, 65. In the 5 use of a large auxiliary supply system, such as that illustrated and comprising the supply tanks 33, 34, and the means for circulating the oil shown and described in connection therewith, it is found that the lubricating 10 oil will not ordinarily be sufficiently purified by precipitation alone within these tanks, and by what purification is secured while the oil is passing through the strainer chambers adjacent the turbines, and therefore 15 I prefer to provide in connection with supply tanks 33, 34, a suitable filtration system, the filter being preferably constructed as shown immediately at the top of one of the tanks, as shown upon the tank 34, the 20 same being indicated by the reference character 70. This filter may be of any suitable construction, the details of the same not being shown herein, but it is preferred that it be provided with filtering chambers accessible 25 through covers 71, 72.

Suction pipes 73, 74 provided with strainers at their lower ends run to the bottom of each of the tanks 33, 34 and are in communication with the common pipe 75, each being 30 valve controlled at 76, 77. The pipe 75 leads to a small steam pump indicated at 78.

79 is a steam pipe supplying steam to pump 78 and is controlled by a globe valve 80, which has an operating lever 81, adjustably 35 connected at 82 with a rod 83 which is provided with a float 84 at its lower extremity, the same being located within the stand-pipe 85. The stand-pipe 85 is provided with pipes as indicated at 86, 87 which 40 lead to the filtering chambers within the filter 70. It is found under some conditions desirable to raise the temperatures of the oil within the stand-pipe before passing it to the filters, and a convenient means for doing 45 this is illustrated, the pipe 95 running from steam pump 78, being designed to conduct the exhaust steam from the pump to the coil 96 indicated in dotted lines in Fig. 1, in the bottom of the stand-pipe 85. The 50 drip from the coil 96 is discharged through the walls of the bottom of the stand-pipe by the pipe 88.

In the oil circulating filtration system above described, it will be apparent that the oil may be circulated at all times to the machines to be lubricated without in any manner interfering with filtration. If there is dirty oil in both tanks, the handles 48, 55 can be positioned in opposite directions and oil taken from one tank and delivered to the other, and one of the tanks emptied for the purpose of cleaning. From the construction of the filtration system as above described, it 55 will be seen that upon the operation of steam pump 78, oil may be taken through the feed

pipe 73 or feed pipe 74 at the option of the operator under the control of valves 76, 77. When the oil is pumped to a predetermined height in the stand-pipe 85, the float controlled valve 80 will be operated to stop the 70 pump when the oil reaches the desired level, in the stand-pipe. Oil from the stand-pipe flows to the filter casing 70 through feed pipes 86, 87 and the filtered oil is discharged 75 optionally through pipe 97 which is branched as indicated at 98, 99, the first said branch entering the tank 34 and being controlled by valve 91, while the last branch enters tank 33 and is controlled by valve 90.

In order to drain the system immediately 80 connected with each of the turbines, the upper extremities of the over-flow pipes 42 within the overflow chambers 41, are preferably made removable, as indicated at 42^a, which will allow the oil to run from the sys- 85 tem to the drain pipe 42.

The auxiliary circulating system which has above been described and which is added to the lubricating system first described, in connection with the turbine machines, is not 90 necessarily regularly used to furnish the turbine with oil and might be allowed to stand idle ready to be thrown instantly in use when required. On the other hand, the system consisting of the pumping and filtration immediately connected with tanks 33, 34, would not be substituted for the usual and first described turbine oil lubricating 95 system, as the turbine pump 12 is directly connected to the machine as described and 100 cannot be stopped without stopping the turbine. But this auxiliary system comprising the pumping and filtration means immediately connected with tanks 33, 34, is adapted to work in conjunction with the turbine 105 system and would in addition be able to fully supply the turbine with oil in case the turbine pump should become entirely inoperative. Under such conditions, it will be seen that the pump 30 of the auxiliary 110 system would supply through pipe 25 oil to the main 36 when the valve 26 is open, and the electric circuit to the motor driven pump 30 closed under such conditions, the oil 115 would pass the valves 25, and be forced into the bearings at 19 in the turbine. The valve 23 would close, being a check valve which would prevent oil from being forced outwardly into pipe 22 and coil 20. This would make it possible to entirely cut off the operation of the ordinary turbine oiling system in case of a break-down and repairs were necessary while the turbine was in operation, since the oil would be supplied to the 120 bearings 19 of the turbine 10 and the drip would be discharged through pipe 14, and through the overflow back to the auxiliary 125 system.

In order that the invention might be fully understood the details of the preferred em- 130

bodiment have been specifically shown and described, but it is not desired to be limited to the exact details shown for it will be apparent that those skilled in the art may 5 make many modifications without departing from the purpose and spirit of the invention.

I claim:

1. In combination with a machine having 10 a direct connected lubricating pump, of a regular oil supply controlled by said pump, an auxiliary oil supply which may be supplied to said machine at will independently of said regular oil supply and pump, and an 15 overflow which returns surplus oil to this outside supply.
2. The combination with a machine having 20 a direct connected lubricating pump, of a regular oil supply controlled by said pump, an auxiliary oil supply, a pump for moving the auxiliary supply, and means for simultaneously opening the auxiliary supply to admit oil to the machine and for starting the said pump.
3. The combination with a machine having 25 a direct connected lubricating pump, of a regular oil supply provided with a valve control, an auxiliary oil supply under the control of a pump, means for operating said pump, and means for simultaneously 30 opening the auxiliary supply to admit oil to the machine and for actuating the pump.
4. In a force feed lubricating system for 35 machines, the combination with a machine to be lubricated, of a regular system adapted to be operated by a pump directly controlled by the machine, an auxiliary supply system, a feeding pipe leading from the auxiliary system to the regular lubricating system of the machine and being provided with 40 a valve under the control of the operator, an overflow which returns surplus oil from the main to the auxiliary system, and a check

valve in the main feed pipe of the regular system between the bearings to be lubricated 45 and the direct connected pump.

5. In force feed lubricating apparatus for machines, the combination with the machine to be lubricated, of an oil pump directly driven by the machine, pipe connections leading from 50 the said pump to the machine and from the machine to the pump, an auxiliary supply system with an outlet pipe tapping the pipe of the regular system between the pump and the bearings to be lubricated, a valve under 55 the control of the operator for admitting oil from the auxiliary supply into the regular system, and a check valve in the regular system between the directly driven pump and the parts to be lubricated to prevent the back 60 flow of oil from the auxiliary to the regular system.

6. In a lubricating system for machines, the combination with the machine to be lubricated, of an oil circulating system 65 therefor comprising a receptacle, an overflow regulator and a pump, storage means comprising two separate compartments, means connecting the overflow regulator with either of said compartments at will, 70 an auxiliary oil replenishing system comprising a motor pump, means connected therewith for drawing oil from either compartment at will and delivering it to the machines to be oiled, and a valve controlling 75 said means adapted to energize the pump motor when the valve is opened.

In testimony whereof I have signed my name to this specification, in the presence of two subscribing witnesses, on the 7th day 80 of February, A. D. 1912.

WILLIAM L. MORRIS.
